ADJUSTABLE WINDOW SHADE AND DRAPERY HANGER

Filed Sept. 2, 1924

Patented June 8, 1926.

1,587,680

UNITED STATES PATENT OFFICE.

LULA ROBINSON, OF DALLAS, TEXAS.

ADJUSTABLE WINDOW SHADE AND DRAPERY HANGER.

Application filed September 2, 1924. Serial No. 735,298.

This invention relates to window shade and drapery hangers and refers more particularly to a device of this character adapted to be adjustable horizontally to conform 5 with the width of a window.

Another object of the invention resides in a means provided for slidably raising and lowering the hangers, either to adjust the shade or drapery thereon or to remove the 10 same therefrom, thus making this adjustment conveniently accessible from the floor.

A feature of the invention lies in its compact, durable, simple construction and its 15 adaptability, due to its adjustments, for its convenient attachment to windows of varying sizes.

Also in this arrangement, suitable lighting provisions are established without difficulty due to the means provided for securing 20 of the hanger at any point across the upper sash of the window.

Other objects, features and advantages will be set forth more fully as the description proceeds, taken in connection with the 25 supplemented drawings forming a part hereof and in which:

Figure 1 represents the invention illustrated in attachment to the window frame, with a portion of the shade cut away.

30 Figure 2 represents a longitudinal rear view of the member upon which the shade or drapery curtain is hung.

Figure 3 represents a front view thereof.

Figure 4 is a plan or top view.

35 Figure 5 represents a preferred form of friction brace for the adjusting rods on either side of the window.

Figure 6 represents a side view of a window, showing the invention as it appears 40 secured thereon.

The following is intended to be a clear and concise description of the invention wherein each part thereof is described, and its function: wherein 1 denotes an ordinary 45 window frame, on either side of which is screwed or otherwise suitably secured a pair of metal strips 2—2 extending half the length thereof. These strips are adapted to provide necessary guides or tracks for 50 the device, in the manner illustrated clearly in Figure 1.

The horizontal member upon which the curtains are adapted to be hung, consist of a plurality of parts, a more comprehensive 55 idea of which may be obtained by reference to Figure 4. A metal strip 3, slidably se-

cured to the housing 4 by means of the collar 5 is provided with an L shaped member 6, adapted to engage one of the tracks 2—2. This strip 3 is slidable within a second housing 5^a. A similar arrangement is provided on the opposite end for the horizontal adjustment of the device, which horizontal adjustment is obtained by loosening the screws in the slots 5^a over which its collar 5 is situated. The L shaped members 6 are drawn outwardly against the tracks 2—2 at which time the screws are tightened to hold the members 6—6 rigidly in position against the tracks.

The two members 7—7, situated on either end of the device lie flush with the facing of the window and are adapted to slide thereupon. These members also carry the 75 brackets 8—8 for supporting the curtains, and upon which suitable brackets may be secured for mounting lace curtains, draperies and the like.

It will be noted by reference to Figure 3 in the drawings, in order that shades of varying widths may be used, the shade brackets 8—8 may be adjusted longitudinally on the hanger which adjustment is separate from that of the hanger, said latter adjustment being made by means of the centrally situated set screw 9^a. A suitable collar 10 is provided as a means for strengthening the hanger. This collar is shown in broken lines.

One form of raising and lowering the hanger upon the window is illustrated in the drawing and shown in detail in Figure 5 thereof. This means consist of a pair of rods 11—11 situated on opposite sides of the window 1, the upper ends of which are removably secured to the lower portions of the member 7—7. The rods are extended downwardly through a friction eyelet 12 and terminate in a suitable handle 12^a. The eyelet 12 aforementioned is provided with a pressure spring 13 which spring is adapted to press outwardly against the rod 11, thus retaining the same in any desired position.

It is desired that the invention not be limited specifically to the locations of the raising and lowering means shown in the accompanying drawings and that the same may be positioned centrally the hanger if desired, and also that other minor changes may be made in the invention as fall within the scope and meaning of the following claims:

1. In an adjustable curtain and shade hanger, a pair of strips slideable within oppositely disposed channel members; tracks, consisting of a pair of strips adapted to be suitably secured on either side of the window frame, a longitudinally adjustable collar secured to the outer end of one of the channel members and having an L shaped member: said L shaped member slideable vertically upon one of said tracks; a like collar secured to the outer end of one of the metal strips on the opposite end of said hanger, and having an L shaped member adapted to slidably engage the other of the vertical tracks and, means for raising and lowering the hanger in relation to the upper half of a window. 40
2. In a hanger of the type set forth, a pair of oppositely disposed channel members; a pair of oppositely disposed strips slideable in said members, longitudinally adjustable curtain supporting means carried by the outer end of one of the channel members and the outer end of one of the strips, longitudinally adjustable collars carried by the outer ends of said channel members and strips, guide strips formed for securement to a window frame, means on the collars to engage said guide strips, rods secured to said hanger to adjust the same vertically of the frame and means to retain the hanger in adjusted positions with respect to said frame. 45
3. A hanger for curtains consisting of a pair of strips slideable longitudinally within a pair of channel members; tracks comprising a pair of strips adapted to be disposed oppositely on either side of an opening; a collar on each end of the said hanger; means in rigid attachment to the collar to engage said tracks to provide for the vertical adjustment of the hanger; said collar movable horizontally in slots in each end of said hanger; means on each end of the hanger for supporting a curtain; said means adjustable longitudinally of the hanger; means for raising and lowering the hanger in relation to an opening; and means for retaining the raising and lowering means in any desired position. 50
4. In a curtain hanger, a pair of tubular members, a pair of strip like members slideable in said tubular members, vertical tracks, independently adjustable collars connecting said strip like members and tubular members, track engaging means carried by said collars and movable therewith, curtain supports connected to the outer ends of the pairs of members and means to shift the hanger vertically with respect to a window frame. 55
5. In a curtain hanger, a pair of tubular members, a pair of strip like members slideable in said tubular members, vertical tracks, independently adjustable collars connecting said strip like members and tubular members, track engaging means carried by said collars and movable therewith, plates connected to the outer ends of one of the pair of members and adapted to slidably engage the front face of a window frame, longitudinally adjustable curtain supports connected to said plates, and means connected to said plates to shift the hanger vertically with respect to a window frame. 60

In testimony whereof I have signed my name to this specification.

LULA ROBINSON.
